UNITED STATES PATENT OFFICE.

EDWARD COLTON BOYCE, OF WASHINGTON, DISTRICT OF COLUMBIA.

VENDING APPARATUS.

1,424,074.

Specification of Letters Patent. Patented July 25, 1922.

Application filed June 7, 1922. Serial No. 566,574.

To all whom it may concern:

Be it known that I, EDWARD C. BOYCE, of Washington, in the District of Columbia, a citizen of the United States, have invented 5 certain new and useful Improvements in Vending Apparatus, of which the following is a specification.

My invention relates to improvements in vending apparatus and refers particularly to 10 an apparatus, coin controlled and operated, which is desirable in dispensing or vending food, although it may be used for any purpose where it would operate in an efficient and practical manner. 15 One object of my invention is the provision of a vending apparatus which will be composed of a small number of parts to insure simplicity, durability and cheapness of production to withstand the hard and in- 20 cessant usage to which such an apparatus is subjected and which will be absolutely reliable and certain in operation.

Another object of my invention is the provision of an apparatus of the character 25 described which will present an ornamental and attractive appearance to provide a handsome store service equipment and which will be seductive and inviting to the purchaser of food.

Another object of my invention is the provision of a vending apparatus which can be easily adjusted to deliver the food according to the amount of coin deposited 30 and which will be of compact and small 35 size to occupy a small space and provide a large capacity for food delivery.

Another object of my invention is the provision of an apparatus of the character 40 stated which will protect and preserve the food in a clean and sanitary manner, but which, upon the deposit of the proper coin, will instantly display the food for delivery.

Another object of my invention is the provision of a vending apparatus whose 45 separate units will project out from the wall or supporting structure to display the food upon their delivery tables in plain view of the customer.

Another object is the production of an apparatus which will insure a great saving of time, as upon deposit of the proper coin or coins, it will open instantly the the cover and permit removal of the food, thus employing a single operation, in contrast to 55 present apparatuses which require at least three separate operations.

With these and such other objects in view as inhere to an invention of this character, the said invention broadly stated consists of a food table or support, a rotatable protecting cover or guard, and means actuated by a coin for releasing said protecting cover and displaying the food upon the table or support.

The invention further consists of a vend- 65 ing apparatus embodying novel features of construction and combination of parts sub-stantially as described and particularly de-fined and distinguished by the claims, and substantially as illustrated in the accom- 70 panying drawings, in which:

Figure 1 represents a front elevation of a series of my vending units to show their exterior appearance and the manner of ar-rangement in the masonry or support. 75

Fig. 2 represents a front elevation of one of the vending units shown on an enlarged scale.

Fig. 3 represents a vertical sectional view through the support and vending unit, and 80

Fig. 4 represents a sectional view on line 3—3 of Fig. 3.

Fig. 5 represents a detail view of a part of the coin operated mechanism, with the parts in released position. 85

Referring by numeral to the drawings in which similar numerals of reference are em-ployed to denote the same parts in all the views:

The numeral 1 designates a wall or sup-90 port of my suitable material and disposed vertically, which is provided with a series of openings 2, in which is mounted the metal frames 3, and secured to said support or wall at the base of said openings are the 95 food supporting platforms 4, which are of substantially circular form and are rigidly attached by means of the brackets 5.

It will thus be noted that the support is 100 provided with a series of openings sur-rounded by metal frames and that a series of food supporting platforms are secured at the base of said openings and in connection with said openings and platforms are arranged the vending units which comprise my appa-ratus, and as each unit is identical I will 105 describe the single mechanism as shown most clearly in Figs. 3 and 4.

To the wall or support is fastened the socket plate 6, which is formed with a 110 threaded opening 7 to receive the threaded stem 8, forming the support of the hub 9,

which hub is freely movable around said stem upon the ball bearings 10, mounted in the track 11, of said stem, and secured to said hub by means of the pair of clamping disks 12, is the curved glass cover or dome 13. This construction it will be observed supports the cover rotatably or swingingly upon the stem 8 and permits it to be swung around to entirely uncover the food supporting table or platform 4, and to cause said cover to instantly swing open I provide the spring 14, one end of which is connected to the hub 9, and the other end is connected to the bracket 15, to which bracket is also hinged at 16, the hood or cover 16', which completely seals and protects the food as well as permits insertion of the food as circumstances require.

From this construction it is evident that the glass dome or cover protects the food and when released is moved by the spring to permit access to the food, and to effect the release of the dome or cover to permit it to move under the impulse of the spring, I provide the coin delivery chute 17 which communicates with the entrance slot 18 at the exterior, which chute is provided with the discharge or lower conical portion 19, and intermediate of said chute is pivoted at 20, the lever 21, which at one end is provided with an adjusting or counterpoise weight 22, and carries at its other end the coin receiver 23, and upon delivery of the coin to the chute 17, said coin falls upon the receiver 23, the effect of which is to tilt said receiver, allowing the coin to fall into and be directed by the tapered delivery chute 19, against the foot 30, of vertical rod 28, movable in guide 29, the upper end of said rod being pivoted to one end of latching lever 24, causing its catch 25 to be released from keeper 26, of cover 13, the cover 13 then being free, is swung open by spring 14 exposing the food for access of the customer. The rod 28 and lever 24 are adjusted to accommodate the proper weight or character of coin by means of the adjusting spring 27.

It will be understood that the adjustable spring 27 can be fixed to operate according to the weight of the coin. It will also be noted that the working parts of my apparatus are few and of simple construction, this assuring an inexpensive, simple and durable mechanism which will withstand the incessant usage and which will prove positive and reliable in operation.

It will be apparent that I provide a vending apparatus which possesses special advantage in automatically serving food and that an apparatus embodying my invention can be manufactured at a very low price, have a large serving capacity in a small amount of space, will prove highly ornamental and attractive and in every particular will prove highly efficient, desirable and practical.

I claim:

1. In a vending apparatus, the combination of a support provided with an opening, a shelf extending from one side of said opening, a rotatable cover for said shelf, means for securing said cover in closed position, coin operated means for releasing said cover, and means for moving said cover to open position when released.

2. In a vending apparatus, the combination of a support provided with an opening, a shelf extending from one side of said opening, a rotatable transparent cover for said shelf, means for securing said cover in closed position, coin operated means for releasing said cover, and means for moving said cover to open position when released.

3. In a vending apparatus, the combination of a support provided with an opening, a shelf extending from one side of said opening, a rotatable dome-shaped transparent cover for said shelf, means for securing said cover in closed position, coin operated means for releasing said cover, and means for moving said cover to open position when released.

4. In a vending apparatus, the combination of a support provided with an opening, a shelf of substantially circular shape extending from opposite sides of said opening, a rotatable cover for one half of said shelf, coin controlled means for releasing said cover, and a manually movable cover for the other half of said shelf.

5. In a vending apparatus, the combination of a support provided with an opening, a shelf extending from one side of said opening, a rotatable cover for said shelf, means for securing said cover in closed position, coin operated means for releasing said cover, a spring for moving said cover to open position when released, a shelf projecting from the other side of said opening, and a protecting cover for said latter shelf.

6. In a vending apparatus, the combination of a support provided with an opening, a shelf extending from one side of said opening, a rotatable cover for said shelf, means for securing said cover in closed position, coin operated means for releasing said cover, a spring for moving said cover to open position when released, said coin operated means consisting of a coin chute disposed in proper relation to said opening and cover, a keeper on said cover, adjustable latching means engaging said keeper, a coin operated lever disposed in proper relation to said chute, a rod connected to said latching means and operated by contact of the coin to release the latching means from the keeper.

7. In a vending apparatus the combination of a supporting structure having an opening therein, a food platform extending from one side of said opening, a platform or shelf extending from the other side of said

opening, a protecting cover for the latter platform or shelf, a rotating transparent cover for the first named platform or shelf, and coin operated means for opening said rotating cover upon the deposit of a proper coin, said coin operated means embodying a coin chute disposed in proper relation to said opening and cover, a keeper on said rotatable cover, adjustable latching means enclosing said keeper, a coin operated lever ar-

ranged in proper relation to said chute, a rod connected to said latching means and operated by contact of the coin to release the latching means from the keeper, and a spring for rotating the cover to open position upon release of said latching means from the keeper.

In testimony whereof I hereunto affix my signature.

EDWARD COLTON BOYCE.
